[57] ABSTRACT

A phased-array antenna (18) for use with a frequency-hopping transmitter (16) includes a plurality of elemental antennas (210), each associated with a phase-shifter (212) which is controlled (20) to form a beam (216) in the desired direction at a base frequency. The antenna elements (210, 212) are formed into subarrays (408, 408b) each of which is fed from a common port (310). A further phase-shifter (312) is associated with each subarray, for imposing a phase shift on a group of elements of the overall array. The further phase-shifters are controlled when the frequency of the transmitter is away from the base frequency, to cause a stepwise-continuous correction phase across the array, which maintains the desired beam direction.

FIG. 1

FIG. 2

FIG. 3

FIG. 4

FIG. 5

FREQUENCY-HOPPING ARRAY ANTENNA SYSTEM

FIELD OF THE INVENTION

This invention relates to antennas, and more particularly to array antennas which are used in systems in which the operating frequency varies rapidly.

BACKGROUND OF THE INVENTION

FIG. 1 is a simplified block diagram of a communication system transmitter, in which a data source 12 is coupled to a frequency-hopping modulator 14, which simultaneously frequency hops at a rapid rate, and modulates the data onto the hopping carrier, as by amplitude or phase modulation, for example. The hopping rate may be equal to the data rate, or it may differ. One possible hopping rate is ten kilohops/second. The modulated carrier is applied over a path 17 to a phased-array antenna 18. Phased-array antenna 18, as known, transmits the signal power into space in one or more beams, under the control of phase-shifter control signals applied thereto over a path 22 from a phase-shifter controller 20.

FIG. 2 is a simplified diagram illustrating a prior-art phased-array antenna which may be used in the system of FIG. 1, as so far described. In FIG. 2, a line array of elemental antennas 210a, 210b, 210c, ..., 210n is fed with RF signals from an array of individual controllable phase shifters 212a, 212b, 212c, ..., 212n, the phase shifts of which are individually controlled by phase shifter control signals applied over a bus 22. The elemental antenna elements are collectively designated 210, and the phase-shifters are collectively designated 212. Each phase shifter 212a, 212b, 212c, ..., 212n, in turn, is fed with RF from a single port or path 17. Those skilled in the art know that the phase shifters of FIG. 2 are controlled to produce a planar wavefront, such as 214, which in turn results in a beam, conventionally illustrated as beam 216, directed in a direction normal to or orthogonal to the planar wavefront 214. The preceding discussion is valid for single-frequency operation, or operation over a narrow band of frequencies. However, when the frequency of operation varies over a significant range, another effect occurs. The phase-shift required to achieve a planar phase front changes with frequency, so that the phase shift at a first or base frequency of operation may be selected to provide the desired planar wavefront direction and resulting beam direction, but will change as the frequency is deviated away from the base frequency. In FIG. 2, the effect of a decrease in frequency, which decreases the required phase-shift imparted by the phase-shifters, is illustrated by a planar wavefront 218, and the change in beam direction is illustrated by beam 220. The offset or "squint" angle due to the frequency change is illustrated as θ . The squint problem can be solved by the use of controllable delays instead of phase shifters in the arrangement of FIG. 2, because the amount of delay does not vary with frequency in an ordinary delay line. However, delay lines, and especially controllable delay lines suitable for high-power applications, tend to be heavy, bulky, and expensive. Consequently, phase shifters are preferred.

It is possible to arrange phase control 20 of FIG. 1 to readjust the phase shifters 212a-212n of the phased-array antenna of FIG. 2 each time the frequency is changed. The calculations required to determine the phase shift required for each phase shifter are not trivial, however, so ultrafast controllers may be required, depending upon the rate of frequency hopping,

which controllers are capable of performing the calculations within the time allowed for the frequency hop. As an alternative, a plurality of predetermined phase values can be stored in memory, with the phase control value for each phase shifter at each frequency and each beam angle stored in memory, and accessed for control of the phase shifters. This arrangement is disadvantageous because it requires substantial memory capacity for each phase shifter if a significant number of frequencies and beam directions are to be available. If small memories are used, the number of beam directions and frequencies of operation will likewise be limited.

Improved frequency-hopping phased-array systems are desired.

SUMMARY OF THE INVENTION

An array antenna for use with a frequency-hopping signal includes an array of antenna elements, each for transducing electromagnetic signals between space and a corresponding RF port of the antenna elements. A phase-shifter is coupled to the RF port of each of the antenna elements of the array of antenna elements, for phase-shifting the signals under the control of beam direction control signals. A beam direction control signal generator is coupled to the phase-shifters, for controlling the phase shift of each of the phase-shifters, in a manner selected for forming at least one beam in a selected direction. Either a source or a sink of frequency-hopping RF signals is provided, for generating or receiving the frequency-hopping signals, respectively, and for generating frequency-indicative control signals representative of the instantaneous frequency of the frequency-hopping signals. A coupler coupled to the phase-shifters and to the source or sink, as the case may be, couples the frequency-hopping signals between the phase-shifters and the source or sink, whereby a corresponding one of a transmit and receive beam is generated by the array. Changes in frequency of the frequency-hopping RF signals causes deviations of the antenna beam from the selected direction. The coupler further includes (a) a grouping arrangement coupled to predetermined groups of the phase-shifters, for grouping the phase-shifters and their associated antenna elements into plural subgroups, each including a subgroup feed port, and (b) additional phase shifters coupled to each of the subgroup feed ports, for controllably shifting the phase of the RF signals applied to the antenna elements of each of the subgroups. An antenna beam correction controller is coupled to the additional phase-shifters and to the source or sink, for generating beam direction correction signals in response to the frequency-indicative control signals, for generating a group phase shift of the RF signals which tends to offset the deviations of the beam from the desired direction. In a particular embodiment of the invention, the antenna beam correction controller is coupled to the beam direction control signal generator, for adjusting the amount of group phase shift in response to the phase shift commanded thereby. The hopping frequencies are therefore grouped into sets, and the elemental phase shifters are controlled at one frequency within the set, preferably the center frequency. The correction phase shifters are controlled at each frequency hop.

DESCRIPTION OF THE DRAWING

FIG. 1 is a simplified block diagram of communication system including a frequency-hopping transmitter and a phased-array antenna;

FIG. 2 is a simplified block diagram of a prior-art phased-array antenna which can be used in the arrangement of FIG. 1;

FIG. 3 is a simplified block diagram of an antenna according to the invention, which can be used in the arrangement of FIG. 1 to form a communication system according to the invention;

FIG. 4 is a simplified block diagram of a beamformer which can be used in conjunction with an array of antenna elements to produce a phased-array antenna according to the invention; and

FIG. 5 illustrates a receiving system according to an aspect of the invention

DESCRIPTION OF THE INVENTION

Initially, it should be stated that the words used to describe antennas are subject to several conventions. Antennas are devices which transduce electromagnetic energy between a port and free space. A passive antenna, such as the elemental antennas of FIG. 2, are reciprocal, in that they have the same characteristics, such as impedance at the port, and beam shape, when transmitting signal as when receiving signal. However, as a result of historical accident, the terms used for transmission are, in general, different from the terms used for reception. With present-day understanding of antennas, these terms are now usable interchangeably. More often, the operation of an antenna is couched in terms of either transmission or reception, with the other mode of operation being understood from the context. Thus, the port to which an antenna transduces may be termed a "feed" port, regardless of whether the antenna is operating in a transmitting or a receiving mode. In the context of antenna elements associated with phase-shifters, the feed port may be considered to be the phase-shifter "input" port.

In FIG. 3, the elemental antennas **210a**, **210b**, ..., **210n**, and their associated phase shifters **212a**, **212b**, ..., **212n**, are grouped into groups of N antenna-element-and-phase-shifter pairs. For example, the N elemental antennas **210a**, ..., **210b** and their associated phase shifters **212a**, ..., **212b** are grouped, so that they are fed in common with RF at a common feed port **310a**. Similarly, elemental antenna **210c** and its associated phase shifter **212c** is part of a subarray group which is fed at a common RF feed port **310b**. The remaining elements are also grouped into subarrays, which are fed at RF ports which have designation numbers extending through port **310n/N**.

Each subarray port **310a**, **310b**, ..., **310n/M** of FIG. 3 is connected to a further phase shifter **312a**, **312b**, ..., **312n/M**, referred to jointly as **312**. Each of the further phase shifters **312a**, **312b**, ..., **312n/M** in turn is connected for RF signal purposes to common port or path **17**. This arrangement allows control of phase shifters **212a**, **212b**, ..., **212n** by means of phase controller **20** of FIG. 1, as in the case of FIG. 2. As mentioned in conjunction with FIG. 2, beam tilt or squint occurs when the frequency of the carrier deviates from the frequency for which phase shifters **210a**-**210n** are set. According to the invention, the phase shifts for phase shifters **210a**-**210n** are set at a frequency, and the frequency of the carrier signal is allowed to change by a plurality of frequency steps before the phase shifters **210a**-**210n** are reset. Instead, a correction phase command is applied at each frequency step (or for a group of frequency steps), from step phase correction block **24** of FIG. 1, by way of a control path **26**, to the further phase shifters **312a**-**312n/N**, to thereby generate a stepped waveform correction, illustrated as the

dash-line waveform **318** in FIG. 3. This dash-line stepped or piece-wise continuous waveform **318** approximates, at the changed frequency, the desired waveform **214**, established by the phase shifters **212a**-**212n**, and generates a beamshape and beam direction **220** which closely approximates the desired beamshape and direction, namely beamshape and direction **216**. Plot **216** represents the beamshape and direction commanded by phase controller **20** of FIG. 1 at the original or base frequency.

FIG. 4 is a simplified block diagram of an array antenna according to the invention, illustrating a three-dimensional array, together with its beamformers, arranged for two-tier phase control of the vertical beam position. In FIG. 4, the nearest vertical column of elemental antennas is designated **210**, and the elements of the column are broken into vertically disposed subarrays, the uppermost of which is designated **408t**, and the lowest of which is designated **408b**. Within the nearest column of elemental antennas **210**, the individual elemental antennas are designated with a superscript "1", the next column of elemental antennas is designated by the superscript "2", and the elemental antennas of the last vertical column of elemental antennas of a first subsection of the array is designated with a superscript "n", representing n columns. Thus, the nearest column of antenna elements **210** is designated **210a¹**, **210b¹**, ..., **210c¹**, ..., **210d¹**, **210e¹**, ..., **210f¹**. The next or second column of antenna elements has its upper element designated **210a²**, while the two upper elements of the last, nth or most remote vertical column of the nearest subsection, are designated **210aⁿ** and **210bⁿ**. Each elemental antenna element of FIG. 4 is associated with a corresponding beam control phase shifter **212**, which are designated in a manner similar to the designations of their associated antenna elements. Thus, antenna elements **210a¹**, **210b¹**, ..., **210c¹**, ..., **210d¹**, **210e¹**, ..., **210f¹** are associated with corresponding phase shifters **212a¹**, **212b¹**, ..., **212c¹**, ..., **212d¹**, **212e¹**, ..., **212f¹**, respectively. Also, antenna elements **210a²**, **210aⁿ** and **210bⁿ** are coupled to their respective phase shifters **212a²**, **212aⁿ** and **212bⁿ**.

As mentioned, the antenna elements and their associated phase shifters in each vertical column of FIG. 4 are broken into vertically disposed subgroups. The elemental antennas **210d¹**, **210e¹**, ..., **210f¹**, and their associated phase shifters **212d¹**, **212e¹**, ..., **212f¹** are fed by 1:N vertical column beamformer **410b¹**. Additional 1:N vertical column beamformers **410b²**, **410bⁿ**, and other vertical column beamformers (not illustrated) lying between vertical column beamformers **410b²** and **410bⁿ** feed other bottom vertical column subgroups (not illustrated).

The vertical column beamformers of each vertically disposed subgroup of FIG. 4, such as subgroups **408t** and **408b**, are fed by horizontal beamformers **412**. More particularly, each output port **413a¹**, **413a²**, ..., **413aⁿ** of a 1:M horizontal row beamformer **412a** is coupled to the input port of a corresponding one of vertical column beamformers **410a¹**, **410a²**, ..., **410aⁿ**, each output port **413b¹**, **413b²**, ..., **413bⁿ** of a 1:M horizontal row beamformer **412m** is coupled to the input port of a corresponding one of vertical column beamformers **410b¹**, **410b²**, ..., **410bⁿ**, and other horizontal row beamformers (not illustrated) of beamformer group **412**, which lie between horizontal row beamformers **412a** and **412m**, have output ports coupled to other vertical column beamformers, which in turn feed other elemental antennas and their phase shifters of other vertical subgroups.

Each horizontal row beamformer of group **412** of beamformers is fed from a subarray level phase shifter **312**; for example, horizontal row beamformer **412a** is fed by a

subarray level phase shifter **312a**, horizontal row beamformer **412m** is fed by a subarray level phase shifter **312m**, and those horizontal row beamformers (not illustrated) lying between horizontal row beamformers **412a** and **412m** are fed by other phase shifters (not illustrated) lying between phase shifters **312a** and **312m**. Subarray level phase shifters **312a**, **312m**, and the other such phase shifters lying therebetween, are fed from the output ports of a 1:Y vertical column beamformer **414¹**. More specifically, phase shifter **312a** is fed from the uppermost output port **414a** of vertical column beamformer **414¹**, and phase shifter **312m** is fed from the lowermost output port **414m** of vertical column beamformer **414^m**. The common port of vertical column beamformer **414¹** is fed over a path **482¹** from an output port of a 1:Z horizontal beamformer **484m**, the common input port of which is designated **486**, and which represents the input port for the entire antenna array of FIG. 4. Other output ports of 1:Z horizontal row beamformer **484** are coupled to arrangements similar to that so far described in relation to FIG. 4.

In FIG. 4, the nearest vertical column of elemental antennas of the furthest subgroup is designated **1210**, just as the nearest subgroup of antenna elements is designated **210**, and the elements of the column are broken into vertically disposed subarrays. The uppermost subgroup is designated **1408t**, and the lower ones are designated **1408b**. Within the nearest column of elemental antennas **1210** of the furthest subgroup, the antenna elements **1210** are designated **1210a¹**, **1210b¹**, . . . , **1210c¹**, . . . **1210d¹**, **1210e¹**, . . . **1210f¹**. The next or second column of antenna elements has its upper element designated **1210a²**, while the two upper elements of the last, n^{th} or most remote vertical column of the furthest subsection, are designated **1210aⁿ** and **1210bⁿ**. Antenna elements **1210a¹**, **1210b¹**, . . . **1210c¹**, . . . **1210d¹**, **1210e¹**, . . . **1210f¹** are associated with corresponding phase shifters **1212a¹**, **1212b¹**, . . . **1212c¹**, . . . , **1212d¹**, **1212e¹**, . . . **1212f¹**, respectively. Also, antenna elements **1210a²**, **1210aⁿ** and **1210bⁿ** are coupled to their respective phase shifters **1212a²**, **1212aⁿ** and **1212bⁿ**.

The elemental antennas **1210a¹**, **1210b¹**, . . . , **1210c¹** of upper subgroup **1408t** of FIG. 4, and their associated phase shifters **1212a¹**, **1212b¹**, . . . , **1212c¹**, are fed by a 1:N vertical column beamformer **1410a¹**. Additional 1:N vertical column beamformers **1410a²** and **1410aⁿ** feed the vertical subarray including top elemental antenna **1210a²** and its associated phase shifter **1212a^{2m}**, vertical column beamformer **1410aⁿ** feeds the vertical subarray including top elemental antennas **1210aⁿ** and **1210bⁿ** and their associated phase shifters **1212aⁿ** and **1212bⁿ**, and other vertical column beamformers (not illustrated) lying between vertical column beamformers **1410a²** and **1410aⁿ**, feed other vertical column subgroups (not illustrated). Similarly, elemental antennas **1210d¹**, **1210e¹**, . . . , **1210f¹** of lower subgroup **1408b** of FIG. 4, and their associated phase shifters **1212d¹**, **1212e¹**, . . . , **1212f¹**, are fed by a 1:N vertical column beamformer **1410b¹**. Additional 1:N vertical column beamformers **1410b²** and **1410bⁿ** feed other vertically disposed subarrays of elemental antennas and their associated phase shifters.

The vertical column beamformers **1410a¹**, **1410a²**, . . . , **1410aⁿ**, **1410b¹**, **1410b²**, **1410bⁿ**, of vertically disposed subgroups **1408t** and **1408b**, and of other corresponding vertically disposed subgroups, are fed by horizontal beamformers **1412**. More particularly, each output port **1413a¹**, **1413a²**, . . . **1413aⁿ** of a 1:M horizontal row beamformer **1412a** is coupled to the input port of a corresponding one of vertical column beamformers **1410a¹**, **1410a²**, . . . , **1410aⁿ**, each output port **1413b¹**, **1413b²**, . . . **1413bⁿ** of a 1:M horizontal row beamformer **1412m** is coupled to the input

port of a corresponding one of vertical column beamformers **1410b¹**, **1410b²**, . . . , **1410bⁿ**, and other horizontal row beamformers (not illustrated) of beamformer group **1412**, which lie between horizontal row beamformers **1412a** and **1412m**, have output ports coupled to other vertical column beamformers, which in turn feed other elemental antennas and their phase shifters of other vertical subgroups.

Each horizontal row beamformer of group **1412** of beamformers is fed from a subarray level phase shifter **1312**; for example, horizontal row beamformer **1412a** is fed by a subarray level phase shifter **1312a**, horizontal row beamformer **1412m** is fed by a subarray level phase shifter **1312m**, and those horizontal row beamformers (not illustrated) lying between horizontal row beamformers **1412a** and **1412m** are fed by other phase shifters (not illustrated) lying between phase shifters **1312a** and **1312m**. Subarray level phase shifters **1312a**, **1312m**, and the other such phase shifters lying therebetween, are fed from the output ports of a 1:Y vertical column beamformer **414¹**. More specifically, phase shifter **1312a** is fed from the uppermost output port **1414a** of vertical column beamformer **414¹**, and phase shifter **1312m** is fed from the lowermost output port **1414m** of vertical column beamformer **414^m**. The common port of vertical column beamformer **414¹** is fed over a path **482¹** from an output port of 1:Z horizontal beamformer **484m**. As mentioned above, the common input port **486** of horizontal beamformer **484m** is the input port for the entire antenna array of FIG. 4. Other output ports of 1:Z horizontal row beamformer **484** are coupled to arrangements similar to those so far described in relation to FIG. 4.

As mentioned, vertical column beamformers **414¹** and **414^m** are fed from corresponding output ports **482¹** and **482^m** of horizontal row beamformer **484** of FIG. 4. Similarly, vertical column beamformers **414²** and **414³**, and all the other vertical column beamformers lying between column beamformers **414³** and **414^m**, are fed, over paths designated **482²**, . . . by the outputs of horizontal row beamformer **484**.

The size of each subarray is selected to achieve a beam width that will maintain an instantaneous bandwidth which is greater than, or at least equal to, the hopping bandwidth of the signal which is transmitted. The elemental phase shifters **212**, **1212** set the nominal beam direction, and the correction phase is simply a positive or negative delta or change of the phase settings of the subarray phase shifters **312**, **1312**. The elemental phase shifters are set to produce a beam in the desired direction at one frequency within a subset of frequency hops, for example at the center frequency of a set of five frequencies, and at the other four frequencies, the elemental phase shifters are left at the original setting, and only the correction phase shifters are reset at each frequency hop to maintain the beam in the desired direction.

FIG. 5 illustrates a receiving system according to an aspect of the invention, in which elements corresponding to those of FIGS. 1 and 3 are designated by like reference numerals. In FIG. 5, the RF signals appearing on path **17** are applied to a downconverter **510**, which downconverts the RF to an intermediate frequency (IF) or to baseband, with the aid of a reference frequency from a frequency synthesizer **512**. The frequency of synthesizer **512** may be established, in known fashion, by a known coding device, such as a logical pseudorandom signal generator **520** in conjunction with a clock signal from a generator **518** controlled by the received signal. The downconverted data or recovery signal is then available from downconverter **510** for use by utilizing apparatus **518**.

The nominal beam direction of the array of elemental antennas **210a**–**210n** is established by the settings of

elemental phase shifters 212a-212n established by phase control block 20. The elemental phase shifters 212a-212n are updated by the pseudorandom signal from generator 520, latched by a latch 524 every 1/N clock cycles by a divider 526.

The array according to the invention is very advantageous in reducing the control requirements of a phased-array antenna in a frequency-hopping environment. For example, a 4096-element array with 4096 elemental phase-shifters could be subdivided into 64 subarrays, with each subarray controlled by a correction or further phase-shifter. In this arrangement, only 64, rather than 4096, phase shifters must be updated at each hopping cycle. In such an arrangement, the elemental phase shifters would only have to be updated to correct the beam direction in response to relative motion between the antenna and the target. Even for airborne antennas, this is a relatively slow correction, easily accommodated.

Other embodiments of the invention will be apparent to those skilled in the art. While the arrangement of FIG. 1 illustrates application of the modulated signal from modulator 14 directly to phased-array antenna 18, a power amplifier could be used to raise the power of the modulated signal, thereby reducing the need for amplification.

What is claimed is:

1. An array antenna for use with a frequency-hopping signal, said array antenna comprising:

an array of antenna elements, each for transducing electromagnetic signals between space and a corresponding RF port;

phase-shifting means coupled to the RF port of each of said antenna elements of said array of antenna elements, for phase-shifting said signals under the control of beam direction control signals;

beam direction control signal generating means coupled to said phase-shifting means, for controlling said phase shift of each of said phase-shifting means in a manner selected for forming at least one beam in a selected direction;

one of a source and sink of frequency-hopping RF signals for one of generating or receiving said frequency-hopping signals, respectively, and for generating frequency-indicative control signals representative of the instantaneous frequency of said frequency-hopping signals;

coupling means coupled to said phase-shifting means and to said one of said source and sink, for coupling said frequency-hopping signals between said phase-shifting means and said one of said source and sink, whereby a corresponding one of a transmit and receive beam is generated by said array, but changes in frequency of said frequency-hopping RF signals cause deviations of said beam from said selected direction; said coupling means further comprising (a) grouping means coupled to predetermined groups of said phase-shifting means, for grouping said phase-shifting means and their asso-

ciated antenna elements into plural subgroups, each including a subgroup feed port and (b) additional phase shifting means coupled to each of said subgroup feed ports, for controllably shifting the phase of said RF signals applied to said antenna elements of each of said subgroups; and

antenna beam correction control means coupled to said additional phase-shifting means and to said one of said source and sink, for generating beam direction correction signals in response to said frequency-indicative control signals, for generating a group phase shift of said RF signals which tends to offset said deviations of said beam from said desired direction.

2. A method for operating an array antenna in conjunction with a frequency-hopping signal, said array antenna including (a) an array of antenna elements, each for transducing electromagnetic signals between space and a corresponding RF port, (b) elemental phase-shifting means coupled to the RF port of each of said antenna elements of said array of antenna elements, for phase-shifting said signals under the control of beam direction control signals, (c) one of a source and sink of frequency-hopping RF signals for one of generating or receiving said frequency-hopping signals, respectively, and for generating frequency-indicative control signals representative of the instantaneous frequency of said frequency-hopping signals (d) coupling means coupled to said elemental phase-shifting means and to said one of said source and sink, for coupling said frequency-hopping signals between said phase-shifting means and said one of said source and sink, said coupling means further comprising (a) grouping means coupled to predetermined groups of said elemental phase-shifting means, for grouping said elemental phase-shifting means and their associated antenna elements into plural subgroups, each including a subgroup feed port and (b) additional phase shifting means coupled to each of said subgroup feed ports, for controllably shifting the phase of said RF signals applied to said antenna elements of each of said subgroups, said method comprising the steps of:

generating elemental beam direction control signals for said elemental phase-shifting means, for controlling each of said phase-shifting means for forming at least one beam in a selected direction at a frequency within a current set of hopping frequencies, whereby a corresponding one of a transmit and receive beam is generated by said array, but changes in frequency of said frequency-hopping RF signals within said current set of hopping frequencies cause deviations of said beam from said selected direction; and

generating group beam correction control signals for said additional phase-shifting means, for generating, at each of said frequencies within said current set of hopping frequencies, a group beam direction control signal, for generating a group phase shift of said RF signals which tends to offset said deviations of said beam from said selected direction.
